UNITED STATES PATENT OFFICE.

CLINTON L. BOPP, OF HAWKEYE, IOWA.

AUTOMATIC RAILWAY SIGNALING SYSTEM.

1,114,427.

Specification of Letters Patent.

Patented Oct. 20, 1914.

Application filed December 16, 1909. Serial No. 533,404.

To all whom it may concern:

Be it known that I, CLINTON L. BOPP, a citizen of the United States, residing at Hawkeye, in the county of Fayette and State of Iowa, have invented certain new and useful Improvements in Automatic Railway Signaling Systems; and I do hereby declare the following to be a full, clear, and exact description of the invention, such as will enable others skilled in the art to which it appertains to make and use the same.

This invention relates to improvements in signaling systems and particularly to automatic signaling systems which indicate at the station or any other point the respective positions of the trains on the system.

The object in view is the arrangement in an automatic railway signaling system of means for indicating the position of the train as the same passes from station to station along the system and in arranging auxiliary means for actuating the indicators should the latter fail to operate as the train passes from station to station.

With these and other objects in view, the invention consists in the combination, construction and arrangement of parts as will hereinafter be more fully described and claimed.

The accompanying drawing is a diagrammatic view of the system.

In constructing a signaling system embodying the present invention, it is designed to provide means whereby the train can cause the operation of indicating means at the station or at hotels or other places for showing exactly where the train is at any given time, and also what progress the same is making which may be determined by timing the trains from one station to the other as the same are shown on the indicator.

Referring to the drawings, it will be seen that the main line wire 1 has indicators connected at intervals shown at A, B and C all of which are connected in series. The indicator A is connected to the positive pole of a battery 62 by means of wire 2, there being interposed between the indicator and battery an impedance coil 64. The negative side of the battery 62 is connected to ground by means of wire 3. The indicator C is connected to the positive side of battery 63 by means of wires 4 and 6', the negative side of the battery 63 being connected to ground by means of wire 5. An impedance

coil 65 comparable with and serving the same functions as the impedance coil 64 is connected between indicator C and the battery 63. Shunted around the indicators A, B and C are condensers 69, 70 and 71 respectively to protect the indicators from static discharges.

As shown in the drawings, there are several switches which are designed to be closed by a passing train and a description of any one of these will be sufficient for all. As shown in the drawings there is connected to the right side of indicator A a wire 6 which connects to a spring 55 located within a housing 7 positioned by the side of one of the rails of the track. Pivotaly mounted within the housing 7 is a contact carrying lever 52 pivotally connected to arm 49 depending from member 48. Secured to the bottom side of the lever 52 is a contact 56 which is adapted to engage the spring contact 55 when the member 48 is depressed by the flange of a wheel, said wheel being indicated at 60. By means of wire 8 the contact 56 is connected to ground. Spring 55 is insulated, as shown, from the housing. An impedance coil 58 is interposed in wire 6 between wire 1 and the contact spring 55. There is provided for each of the indicators one of the switches above described or a similar device for connecting wire 6 to the ground when a train passes. The closing of the switches need be momentary only or just sufficient for energizing the mechanism which actuates the indicators. The indicators may be of any style, a number of which are in common use and it is to be understood that any approved form of indicator can be employed at A, B or C. After the indicators have registered any further use of current is unnecessary so that the switch need be closed only a short time.

At each closing of the circuit by the depression of friction member 48 at the respective stations the indicators will be actuated, for it will be seen that the line wire 1 is constantly charged at a potential different from the potential of the earth so that whenever any one of the contacts 56, engages the corresponding contact 55, the line wire 1 will be connected to ground in which case current will flow from the two batteries 62 and 63 to ground through the closed contacts. For instance, when the switch corresponding to indicator A is depressed or closed as indicated in dotted lines in the drawing

current from battery 62 will flow through impedance coil 64, wire 2, through the indicator A, over wire 1, down wire 6, through impedance coil 58, spring contact 55, contact 56, wire 8 to ground and up from ground through wire 3 and back to battery 62, thus energizing indicator A. At the same time that this circuit is being closed the following circuit is also closed. Current 10 flows from battery 63 through impedance coil 65, up wires 4 and 6' through indicator C, over line wire 1, through indicator B, and over line wire 1 again to wire 6, from where it passes through impedance coil 58, 15 spring contact 55, contact 56, wire 8 to ground up from ground through wire 5 back to the opposite side of the battery 63. Thus, it will be seen that all of the indicators throughout the system have been actuated by the closing of one switch. In order 20 to hold the arm 52 normally in raised position so that the member 48 may be engaged by the flange of a wheel and also for holding contact 56 out of engagement with spring contact 55, there is provided in each housing 7 a spring 54, one side of which engages the housing while the other side engages the under side of the corresponding lever 52. The several impedance 25 coils used are for the purpose of preventing static discharges. The batteries 62 and 63 are necessarily of equal strength to prevent the overpowering of one by the other and therefore setting up a continuous current. 30 Connected adjacent one of the indicators such as A is a device for connecting the line to ground, should this be desired for any purpose. If it should be noted that one of the trains passes a station without actu-

ating the indicator, an attendant can de- 40 press switch 68 which will connect the line wire 1 to ground by the following circuit: wire 66, which is connected to line 1, impedance coil 67, switch 68, wire 10 to ground and it will be understood that when the line 45 wire 1 is thus connected to ground the switches will be actuated just as though any one of the members 48 had been depressed by the flange of a passing train and the signal given thereby. 50

What I claim is:

1. In a signaling system, a closed main line circuit and return, equal but opposed sources of current connected to the line circuit, one at each end of the line, a plurality 55 of switches connected across the line and return adapted to be closed by a passing train, an auxiliary switch connected across the line and return, and step by step indicators interposed in the line circuit. 60

2. In a signaling system, a positively charged line wire connected to the ground at each end, step by step indicators interposed in the line wire and adapted to be operated as current flows through said line 65 wire, means associated with the line wire and track for causing current to flow through the line wire to operate the indicators as a train passes, and an auxiliary switch interposed between the line wire and 70 ground.

In testimony whereof I affix my signature in presence of two witnesses.

CLINTON L. BOPP.
